US00D775562S

(12) **United States Design Patent** (10) **Patent No.:** **US D775,562 S**
(45) **Date of Patent:** **** Jan. 3, 2017**

(54) **GEAR STICK**

(71) Applicant: **Volvo Car Corporation**, Göteborg (SE)

(72) Inventors: **Thomas Ingelnath**, Torslanda (SE);
Robin Page, Västra Frölunda (SE);
Tisha Johnson, Göteborg (SE)

(73) Assignee: **Volvo Car Corporation**, Göteborg (SE)

(**) Term: **15 Years**

(21) Appl. No.: **29/542,825**

(22) Filed: **Oct. 17, 2015**

(30) **Foreign Application Priority Data**

Apr. 23, 2015 (EM) 002687764-0009

(51) **LOC (10) Cl.** **12-16**

(57) **CLAIM**

The ornamental design for a gear stick, as shown and described.

DESCRIPTION

FIG. 1 is a perspective view of a gear stick showing our new design.

FIG. 2 is front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines, where present, in FIGS. 3 and 7 illustrate portions of the gear stick that form no part of the claimed design.

1 Claim, 7 Drawing Sheets
